LIFTING RIG

Leathem D. Smith, Carl R. Christianson, Richard A. Stearn, and Howard H. Hunt, Sturgeon Bay, Wis.; said Christianson, said Stearn, and said Hunt assignors to said Smith; Alva Smith administratrix of said Leathem D. Smith, deceased

Application August 10, 1945, Serial No. 610,148

7 Claims. (Cl. 294—67)

This invention pertains to lifting and hoisting mechanism and has as its principal object the provision of a lifting rig adapted to cooperate with an especially designed container such that the hoisting rig may be quickly lowered upon the container for automatic coupling with the latter to facilitate the loading and unloading of cargo and transport freight.

A more particular object is the provision of a simplified rig and cooperating container means characterized by the fact that the container has especially formed socket or receptacle means which receive formations on the rig for quickly and accurately locating the latter in coupling the same with the container.

A further object is the formation and disposition of locating receptacles on a cargo, freight, or package container in a manner which shall eliminate projections from the body of the container, while utilizing a minimum of space upon and in said container to provide a satisfactory locating and coupling means.

Another object is the provision of a simplified uncoupling means on the rig which shall be entirely reliable in mechanical operation; which shall effect the uncoupling operation quickly and positively; and which shall be of a character to require the minimum of servicing or repair.

Yet another object is the provision of locating formations on the rig adapted to shield the coupling members against accidental release or interference from obstructions or the like without complicating the construction or otherwise rendering the coupling means inaccessible.

Additional objects and aspects of novelty relate to details of the construction and operation of the preferred embodiment hereinafter described, including a quick manual release means accessible for operation from adjoining sides of the rig, and a simplified combination counterbalance and spring means for assuring positive coupling action automatically upon locating the rig on the container, all of which will appear more fully as the following specification proceeds in view of the annexed drawing in which:

Figure 1 is a top plan view of the lifting rig;

Figure 2 is a side elevation of the lifting rig;

Figure 3 is a vertical section along lines 3—3 of Figure 1; and

Figure 4 is a perspective fragment, to enlarged scale, of the container locating and coupling means.

One satisfactory form of construction of the lifting means or rig is shown in Figure 1, and consists essentially of a frame 10 formed of

flanged plates 11 (see also Figure 2) secured together, as by welding or other suitable means, in rectangular or quadrilateral array so as to conform to the shape of the top portion 12 (Figure 3) of a container 13 with which the rig is intended to be used.

The corner junctures of side plates 11 are reinforced with gussets 14 welded to flange portions 15 on the upper edges of said plates.

10 Load carrying members in the nature of I-beam sections 16 and 17 extend diagonally of the frame for attachment, as by welding or the like, to plates 11 and, if desired, to gussets 14, there being additional gussets 18 (Figure 3) secured 15 to the undermost flange faces and plates 11 at the ends of said beams. At the intersection of the beams 16 and 17 (Figures 1, 2 and 3) is a U-bolt 19 extending through tie plates 20 and 21 to afford a central tie for said beams and also 20 an eye for engagement with a crane or hoisting hook.

At the corners of the rig frame are depending 25 locating or guiding members or legs 25 (Figures 2 and 3) having inwardly projecting horizontal seating portions 26 (Figure 3) adapted to rest upon the bottom portions 27 of combination locating and coupling recesses provided at the corners of the container 13, as in Figure 4.

Means for automatically coupling the rig to a 30 container designed for cooperation therewith, includes a plurality, in this instance four, of coupling hooks 30 (Figure 3) each fast on a rod 31 (Figure 1) mounted for rocking movement in trunnions 32 on members 18, rods 31, it being 35 noted, extending in parallelism between opposite sides of the rig, and there being two coupling hooks on each rod.

Also fast on rods 31 are levers 35 disposed at 40 or near corresponding ends of their respective rods adjacent one particular side of the rig. Each lever 35 has connected thereunto one end of a normalizing spring 36, the respective opposite ends of which springs are connected or anchored to the frame so as to yieldably rock rods 45 31 in a counter-clockwise direction.

Means for releasably actuating the coupling 50 means includes a pair of shafts 43 and 44 each provided at its outer end with a small operating handle 42 (Figures 1 and 2) disposed in a recess 43 formed in adjoining plates 11, the inner end portions of these shafts being journaled in the web part of one of the I-beams 16, said end portions of the shafts having fixed thereon coacting 55 mitre gears 44 and 45, whereby rotative or rock-

ing motion of one shaft will be transmitted to the other.

The shaft 40 extends in parallelism with the coupling shafts 31, while the remaining release shaft 41 extends transversely of coupling shaft 31 and release shaft 40, and motion for rocking of the coupling shafts 31 is accordingly taken from release shaft 40 by means of a small sheave 48 (Figures 1 and 3) fast thereon and having a cable 49 wound thereon with opposite ends attached to the free end portions of rocking levers 35 for shafts 31.

Thus, a clockwise turning of either operating handle 42 will result in a movement of the levers 35 inwardly of the frame, and a consequent rocking of the coupling hooks 30 in a direction outwardly of the frame, for purposes hereinafter described.

In Figure 4 is shown the combination locating and coupling formation and means for the container 13, the same consisting of adjoining plate portions 50 and 51 sloping downwardly to a juncture with the seating plate or formation 27, and having contiguous edge portions 52 disposed inwardly from the corner 53 of the container. A coupling recess 54 is provided in plate 51, said recess having a sloping wall portion 55 pitched downwardly toward seating portion 27, and a coupling lug 56 extending across the upper margin of said coupling recess in plate 51, and under which hooks 30 engage in the manner illustrated in Figure 3.

The construction of the locating and coupling formations is uniform excepting that they are made in right and left hand sets for cooperation with right and left hand hooks 30, as will be apparent from Figure 3, there being one of these coupling devices at each of the four upper corners of the container 13.

In the use of the novel lifting rig, containers 13 loaded with freight are handled safely and quickly by lowering the rig from the usual crane, hoist or the like, by means of a hook engaged in eye 19, onto the top of the container and manually guiding the rig so that the locating projections or legs 25 seat in locating and coupling recesses in the manner illustrated in Figure 3 with flange portions 26 of these legs seated upon portions 27 of the recesses.

As the rig seats home on the container, hooks 30, and particularly the downwardly depending counterbalance portions 38a thereof, which are pitched or cammed inwardly of the hook, engage lugs 56, causing the hooks to rock so that the hook portions thereof will engage under the lug portions by action of springs 36 in restoring the hooks to normal position as soon as the rig is fully seated upon the container. Thus, the coupling operation is automatic, as also is the locating operation once the rig is properly oriented by the craneman or stevedore for descent upon the container, it being evident in this connection that the pitching of recess walls 51 and 54, and consequent location of lugs 56, causes the rig to be guided into proper position coincidentally with the slippage of hook portions 38a over lugs 56, as can be visualized from inspection of Figure 3.

When it is desired to release the rig from the container, it is merely necessary to turn one of the handles 42 a fraction of a revolution clockwise, thereby winding in cables 49 a small amount to rock levers 35 in a direction inwardly of the rig, with a consequent rocking of hooks 30 out of engagement with lugs 56, whereupon the rig

is free to be hoisted, hooks 30 being restored to normal position by actions of springs 36 as soon as handles 42 are freed.

The novel rig, inclusive of the container and coupling means thereon, greatly simplifies and expedites cargo handling by reason of the automatic locating and coupling features described. There are no parts exposed to injury or obstructively disposed either on the container or rig, so that the device is especially suited to operation in close quarters such as are encountered in cargo holds and the like, and the containers, by reason of the absence of obstructive projections or parts, lend themselves readily to the most efficient and economical stowage. The foregoing advantages, together with the simplicity and rugged structural and functional qualities of the device, render the same a considerable improvement over prior devices of this class which are objectionable, among other things, because they involve relatively complex structural and operative features, or because of the presence of obstructive parts which are exposed to injury or interfere with stowage in one way or another.

Having thus described our invention, what we claim as new and wish to secure by United States Letters Patent is:

1. A hoisting rig comprising a freight container having upwardly open recessed leg sockets having coupling elements therein mounted at upper corner parts thereof, a frame adapted to fit onto the top of said container and having downwardly depending legs adapted to seat in said leg sockets to guide the frame into predetermined coupling position on said container, and coupling elements mounted on the frame and guidedly engaged with said coupling elements on the container and responsive to movement of said frame into said predetermined position.

2. In a hoisting rig, in combination, a freight container, upwardly open recessed leg sockets having coupling formations therein mounted at upper corners of said container, a rig formed to fit closely against the top of said container, depending guide legs on the rig arranged to seat in said container sockets, and coupling elements associated with each leg on said rig and automatically engageable with said coupling formations on the container by action of lowering of the rig onto the container, together with means on said rig operable to uncouple said coupling means.

3. In a hoisting rig, in combination, a container having a top with corner portions thereon, said corner portions being inwardly recessed with vertically extensive wall portions, a vertically pitched recess in said wall portions at each said corner portion, lug means across each said pitched recess for coupling purposes, and a rig adapted to be lowered upon said top and provided with a plurality of pendant locating projections each receivable in one of said recessed corner portions, together with hook means adjacent each said locating projection and each releasably engageable with one of said lug means when said rig is positioned on said container top to couple the rig to the container.

4. In a hoisting rig, a substantially rectangular frame, hollow locating legs pendant from corner portions of said frame, hook means pivoted within said locating legs, spring means yieldingly pivoting said hook means to a normal coupling position, mechanism movable with said frame and

operable to pivot said hook means from normal position to released position, and container means including coupling elements engageable by said hook means when said frame is disposed on said container means, said coupling means of the container being disposed within leg sockets thereof, said locating legs being disposed in said leg sockets when said hook means is engaged with the coupling means as aforesaid.

5. In combination, a hoisting rig and a cargo container having a top portion adapted for interfitting relation with said rig, upwardly open recesses in said top portion, a hook lug in each said upwardly open recess, hooks on said rig each engageable with one of said lugs for coupling the rig with the container, locating legs depending from the rig interfitting with said upwardly open recesses respectively to dispose the rig in a predetermined coupling position with the container, and means accessible on at least two adjoining sides of said rig for moving said hooks out of coupling relation with corresponding hook lugs.

6. In a hoisting rig, a substantially rectangular frame adapted to be lowered upon a cargo container, a plurality of rock shafts extending in parallelism between opposite sides of said frame, coupling elements on said shafts and movable with their respective shafts in a direction inwardly of the frame and toward the elements on the opposite shaft to a coupling position, means yieldingly urging said shafts to dispose corresponding coupling elements in coupling position, a first release shaft extending from one side of said frame in parallelism with said rock shafts, manipulating means for said first release shaft disposed in a recess in said last-mentioned side of the frame, means operatively interconnecting said first release shaft with said rock shafts whereby the latter may be moved in uncoupling operation, at least, by actuation of said manipulating means, a second release shaft extending in a sense transversely of said rock shafts and having manipulating means disposed in a recess in a second side of said frame adjoining that of said first-mentioned manipulating means, and

25

45

means drivingly interconnecting said release shafts whereby manipulation of either in a predetermined manner will effect rocking movement of all said rock shafts and the corresponding hook means for the purpose set forth.

7. In a cargo handling device, a cargo container having a substantially rectangular top with sockets at the corners thereof and respectively opening into said top and two adjoining sides of 10 said container, said sockets each having a bottom portion constituting a seating ledge and side walls sloping convergently toward the corresponding ledge, each said socket having a recess in one of the said sloping walls thereof, a hook engaging 15 bar across each said recess, together with a substantially rectangular rig adapted to seat down upon said container top and having locating legs at the corners thereof and each adapted to seat home upon one of said seating ledges, and hook 20 means adjacent each said leg and situated for engagement with one of said bars by seating of the corresponding leg in the corresponding socket.
